UNITED STATES PATENT OFFICE.

JOHN HAAG, OF TROUTVILLE, PENNSYLVANIA.

MINER'S TOOL FOR BREAKING DOWN COAL.

SPECIFICATION forming part of Letters Patent No. 367,807, dated August 9, 1887.

Application filed March 8, 1887. Serial No. 230,122. (No model.)

To all whom it may concern:

Be it known that I, JOHN HAAG, a citizen of the United States, residing at Troutville, in the county of Clearfield and State of Pennsylvania, have invented a new and useful Improvement in Miner's Tools for Breaking Down Coal, of which the following is a specification.

The invention is a device designed to be used in breaking down coal after the same has been drilled and undermined in the usual manner for blasting, the object being to avoid the use of gunpowder or other explosive and all the deleterious accompaniments of the same; and it consists in the construction and novel arrangement of parts, hereinafter described, pointed out in the claims, and illustrated in the accompanying drawings, in which—

Figure 1 represents a perspective view of the device or tool with the wedge portion turned sidewise on its pivot. Fig. 2 represents the device in position to be used to break down the coal that has been drilled and undermined in the usual manner.

Referring to the accompanying drawings, A represents the shaft of the device, about four feet long and usually rectangular in cross-section.

a is a head secured upon the outer end of the shaft A by means of a pin thereon entering a recess in the head, which is intended to receive the blows of the hammer when operating the device.

B is an end section, pivoted at b between the sides of the bifurcated inner end of the shaft A. The said section is curved and tapers toward its point b', which is chisel-edged laterally, as shown.

C is the wedge-section, pivoted at c upon the lower surface of the shaft A in a cut-away portion, a', of the same. The said section inclines inward toward the shaft from its pivotal point, and has its inner end, c', beveled and slightly inclined transversely to engage under the corresponding inclined and beveled shoulder, a'', of the shaft A. Thus the wedge-section locks into said shoulder and can be turned to one side thereof only, and makes a continuous surface with the shaft.

The end section curves toward the side of the shaft on which the wedge-section is pivoted, as shown.

The manner of using the device is as follows: The coal being drilled and undermined, 55 the tool or device is inserted into the drill-hole up to the point of the wedge-section, with the point of the end section at the end of the drill-hole, which is gaged to proper depth thereof. It is then in the position 60 shown in Fig. 2, the point of the end section turned slightly downward and the wedge-section on the under surface of the staff. The miner then drives it inward with a hammer or the like, and as it enters the end section, 55 guided by its chisel-edged curved point, turns on its pivot and takes a downward course, and the wedge-section forces downward the coal below the mouth of the drill-opening, so that the coal above the undermining is soon 70 broken away.

The following are some of the advantages derived from the use of the device: The coal can be broken down and carried away in less time than by the use of gunpowder; no time 75 is lost in waiting for smoke to clear away; large amounts of powder can be saved; the miner is preserved from the dangers of explosion and of breathing unwholesome gases generated by the explosion, and there is no danger of shattering the roof of the coal-level and bringing it down on the heads of the miners.

The entire device is preferably made of steel.

Having described my invention, I claim—

1. The herein-described device for breaking down drilled and undermined coal, which device consists of the staff or shaft of suitable length, the curved and tapered end section pivoted to one end of the staff, and the wedge-section pivoted upon one side of the staff near the other end, substantially as specified.

2. The herein-described coal-mining tool or device, composed of the staff provided with the head a, and inwardly beveled inclined shoulder a'', the curved end section having its concavity on the same side of the staff as said shoulder, pivoted within the bifurcated end 100

of the staff, tapering thence to its point and provided with a lateral chisel edge at said point, and the wedge portion pivoted on the staff in the depressed or cut-away portion a' , 5 and having its inner end beveled and inclined to engage with the shoulder a^2 , substantially as specified.

In testimony that I claim the foregoing as my own I have hereto affixed my signature in presence of two witnesses.

JOHN HAAAG.
